Patented Jan. 11, 1927.

UNITED STATES PATENT OFFICE.

FRANZ RAWIE, OF OSNABRUCK-SCHINKEL, GERMANY.

RAILROAD-BUFFER CONSTRUCTION.

Application filed June 1, 1926, Serial No. 113,015, and in Germany November 13, 1925.

This invention relates to a railroad-buffer of the thrust triangle type which is simple in construction and efficient in operation and comprises the use of wooden brake members in connection with the base member of a thrust triangle.

The invention is illustrated on the accompanying drawing.

Figure 1 is a side elevation of one embodiment of the improved buffer construction, some parts being broken away, and Figure 2 is a partial sectional view of one of the buffer thrust triangles. Figure 3 is a partial sectional view similar to Figure 2 of a modified construction.

In Figures 1 and 2 a buffer carrying rail is designated by *a*. *b* is a farther rail, forming an element of the triangle base. The side elements of the thrust triangles are indicated by *c*. *d* designates a wooden brake beam or brake block connected to rail *b* by bolts *e* having coiled springs *f* put thereon which tend to yieldingly press the brake beam *d* against the track rail's head *a*. The illustrated arrangement of the one thrust triangle is also provided for the thrust triangle of the other rail, both triangles as usually being connected together by a buffer beam *g*.

The application of the buffer base as an element of a slide construction results in a particularly simple construction whereas the connection of this metal piece with a wooden brake block ensures proper braking effect by frictional engagement of sliding parts and certain elastic qualities favorable for the transmission of thrust.

It is not essential for the invention that the rails *a* on which the buffer is mounted, are the rails on which the vehicle or train to be stopped by the buffer is running; the buffer may be mounted on separate flanged beams in parallel relation to the track rails. It will be understood that these beams need not to be rails and likewise it is not indispensable that the base element of the buffer consists of a normal rail; any other suitably flanged beam may be used which by its flange is in engagement with the flange of a carrying beam.

In the buffer construction of Figures 1 and 2 it is particularly the strong frictional engagement between the wooden beam *d* and the buffer carrying rail *a* whereon the efficiency of the construction on sliding displacement of the buffer depends. In the

modified construction of Figure 3 it is not so much this function but a certain resiliency of the wood whereon the efficiency of the construction depends, may it be in connection with a sliding arrangement of the buffer, may it be in connection with a buffer of the stationary type. In Figure 3 the reference letter *h* designates the side elements of a thrust triangle, *i* are claw members rigidly secured thereto and firmly gripping the rail or metallic beam *k* on which the buffer is mounted. *l* is a wooden beam firmly connected with the buffer and in tight contact with the upper surface of the beam *k*. On impact of a car or train on the buffer the exerted shock tends to tilt the buffer so as to press down the buffer end remote from the impacting car. Under the effect of this tilting tendency the wooden beam *l* at the said end of the buffer remote from the car is somewhat compressed and it has been found that such compression of an intermediate member of a somewhat elastic and not absolutely rigid nature such as wood materially aids in the taking up of stress, so that with the insertion of such a wooden or the like beam the buffer is adapted to take up much more violent shocks than without same.

What I claim is:—

1. In a railroad buffer construction a thrust triangle mounted on a flanged beam, said thrust triangle having a base element comprising a flanged metallic beam engaging with its flange the flange of the supporting beam, said metallic base element of the thrust triangle connected with a non-metallic friction member contacting with the supporting beam, the triangle adapted to slide along the supporting beam under frictional engagement of said non-metallic member and the supporting beam.

2. In a railroad buffer construction a thrust triangle mounted on a rail, said thrust triangle having a base element comprising a flanged beam engaging with its flange the head of the supporting rail, said flanged beam connected with a non-metallic member contacting with the head of the supporting rail, the triangle adapted to slide along the supporting rail under frictional engagement of said non-metallic member and the head of said supporting rail.

3. In a railroad buffer construction a thrust triangle mounted on a rail, said thrust triangle having a base element comprising a

- rail section engaging with its head portion the head of the supporting rail, said rail section of the triangle base being connected with a wooden member frictionally engaging 5 the lateral surface of the supporting rail head opposite that side of the rail head which is in engagement with the triangle base rail, the triangle adapted to slide along the supporting rail.
- 10 4. In a railroad buffer construction a thrust triangle mounted on a rail, said thrust triangle having a base element comprising a rail section engaging with its head portion the head of the supporting rail, said rail section of the triangle base being yieldingly 15 connected with a wooden member friction-
- ally engaging the lateral surface of the supporting rail head opposite that side of the rail head which is in engagement with the triangle base rail, the triangle adapted to 20 slide along the supporting rail.
5. In a railroad buffer construction a thrust triangle mounted on a rail, said thrust triangle having a base member comprising a wooden beam positioned along the upper 25 surface of the head of the supporting rail and metallic connectors maintaining the triangle in lifting preventing engagement with the supporting rail.

In testimony whereof, I affix my signature. 30

FRANZ RAWIE.
